UNITED STATES PATENT OFFICE.

ERNEST T. HALLOWAY, OF MILWAUKEE, WISCONSIN.

DESIGN FOR AN AUTOMOBILE BODY.

Application filed November 11, 1927. Serial No. 24,085. Term of patent 7 years.

To all whom it may concern:

Be it known that I, ERNEST T. HALLOWAY, a citizen of the United States of America, residing at Milwaukee, in the county of Milwaukee, Wisconsin, have invented a new, original, and ornamental Design for an Automobile Body, of which the following is a specification, reference being had to the accompanying drawings, forming a part thereof.

I claim:

The ornamental design for an automobile body as shown.

ERNEST T. HALLOWAY.
